UNITED STATES PATENT OFFICE.

PAUL ROBINS TRETHEWEY, OF MUSKOKA FALLS, CANADA.

GUARD FOR FREIGHT-CARS.

SPECIFICATION forming part of Letters Patent No. 623,580, dated April 25, 1899.

Application filed February 2, 1899. Serial No. 704,263. (No model.)

To all whom it may concern:

Be it known that I, PAUL ROBINS TRETHEWEY, a subject of Her Majesty the Queen of Great Britain, residing at Muskoka Falls, county of Muskoka, Province of Ontario, Canada, have invented certain new and useful Improvements in Guards for Freight-Cars, (for which Letters Patent of the Dominion of Canada were granted February 16, 1899, No. 62,669, 5 to the application for which was filed February 1, 1899, Serial No. 84,542;) and I do hereby declare that the following is a full, clear, and exact description of the invention, such as will enable others skilled in the art to which it appertains to make and use the same.

My invention relates to an improvement in detachable guards for freight-cars; and it consists in suitable standards provided with eyes through their upper ends and suitable 20 clamps upon their lower ones for securing the standards to the car, a rope or chain which is passed through the eyes at the upper ends of the standards, as will be more fully described hereinafter.

25 The object of my invention is to provide a detachable guard which can be applied to and quickly removed from any freight-car and which serves to prevent the brakeman from falling off the cars.

30 In the accompanying drawings, Figure 1 is a side elevation of a detachable guard which embodies my invention. Fig. 2 is an end view of the same.

35 A represents the roof of a freight or other car, and B the standards of the guard, which are attached to the projecting portions of the running-board by means of the clamps C upon the lower end of each guard. This guard consists of the inwardly-turned end D of the 40 standard, through which the screw E passes vertically, and the projection F, which is provided with the brace G. The projection F catches over the top of the running-board or any suitable place for it, while the upper end 45 of the screw E clamps the under edge of this board and rigidly secures the standards in position. This clamp is used for the purpose

of making the guards attachable to or detachable from any of the freight-cars now in use and dispenses with all other fastenings.

50

Through the upper ends of the standards B are formed suitable eyes or openings, and through these eyes is passed a rope or chain I, which extends from one end of the car to the other at any suitable distance above the roof 55 and which rope or chain forms hand-rail to prevent the brakeman from falling from the cars. Through each of the standards is passed a pin or cleat J, and to these pins or cleats are fastened the ends of the rope or chain in 60 any suitable manner, so that a slack of the rope or chain can be taken up and held perfectly taut.

Heretofore a guard has been attached to a freight-car, but it has been permanently secured thereto, and the construction employed is different and more costly than what is here shown by me. By my construction the guard can be quickly applied to and detached from a car, and hence can be transferred from one 70 car to another, as circumstances require. This detachable feature is a valuable and important part of my invention, for the guards can be taken from those cars which are not in immediate use and applied to those that are, and thus lessen the risks of life and limb of the brakeman.

75 Having thus described my invention, I claim—

A detachable guard for cars, the standards 80 B provided with the inwardly-turned ends D, projections F, and braces G, combined with the screw-clamps E, the ropes or chains that pass through the upper ends of the standards, and the pins or cleats to which the ends of the 85 ropes or chains are fastened, and by means of which they may be tightened, substantially as described.

In witness whereof I have hereunto set my hand in the presence of two witnesses.

PAUL ROBINS TRETHEWEY.
